CLAIM

The ornamental design for a bottle holder, as shown and described.

DESCRIPTION

In a preferred embodiment, the nature of the product is a holder for a bottle suitable to be placed in a bathroom. In a most preferred form, the holder also dispenses fluid from the bottle in an automated fashion.

FIG. 1 is a top, right, front perspective view of a bottle holder embodying our new design;

FIG. 2 is a front elevational view thereof;

FIG. 3 is a right elevational view thereof;

FIG. 4 is a left elevational view thereof;

FIG. 5 is a rear elevational view thereof;

FIG. 6 is a top plan view thereof;

FIG. 7 is a bottom plan view thereof;

FIG. 8 is a top, right, front perspective view of a second embodiment of a bottle holder embodying our new design, the top plan view being identical to the view of FIG. 6, and the bottom plan view being identical to the view of FIG. 7;

FIG. 9 is a front elevational view thereof;

FIG. 10 is a right elevational view thereof;

FIG. 11 is a left elevational view thereof; and,

FIG. 12 is a rear elevational view thereof.

The broken line representations of a push button, bottle holder mating structure, light, screw hole, bottle receiving wall structure, bottle holder support structures, hook mounting structure, and bottle mounting structure in the views are for illustrative purposes only and form no part of the claimed design.
